Hawson & Hawson

UNITED STATES PATENT OFFICE

CHARLES P. GRAY, OF WEST CHESTER, PENNSYLVANIA, ASSIGNOR TO GRAY WIRELET CORPORATION, OF WEST CHESTER, PENNSYLVANIA.

DEVICE FOR MAKING SPIRAL WIRE FASTENERS

Application filed January 30, 1928. Serial No. 250,622.

This invention relates to improvements in devices adapted primarily for securing together sheets of paper, cardboard, cloth and other materials, and more particularly in a 5 device of the character forming the subject of U. S. Patent No. 1,446,343, dated Feb. 20, 1923.

The principal object of the present invention is to provide a simplified and generally 10 more efficient tool for forming the spiral coils constituting an essential part of the fastening element.

In the attached drawings:

Figure 1 is a side elevation of a device made 15 in accordance with my invention;

Fig. 2 is a detached perspective of the coil-forming tool, and

Fig. 3 is a view in perspective of the finished article in one of its forms.

With reference to the drawings, my device in one embodiment comprises a base 1 having thereon a bracket arm 2, the forward end of which is formed to constitute a guide and bearing for a vertically movable and rotary 20 shaft 4. This shaft carries at the bottom a tool 5 which forms the principal element of the present invention and which will be described hereinafter. At the top, this shaft carries a transverse operating arm 6 by means 25 of which the shaft may be rotated, and between the upper end of the guide 3 and a collar 7 on the hub portion of the handle 6 is confined a spring 8 which normally exerts a pressure tending to hold the shaft in an elevated 30 position, as shown in full lines.

The base 1 forms a table beneath the tool 35 position upon which the work or parts to be joined together are laid. In the present instance, this work is in the form of two sheets 40 9 and 10. In joining these sheets together, a wire 11 is used which is passed through the sheets in the present instance in two places from the under side thereof, and in order to permit the work to lie flat upon the table 1, 45 the table is formed with a groove 12 which receives that part of the wire 11 which underlies the work. This groove also functions to hold the wire firmly in predetermined fixed position during the tool operations herein- 50 after described.

In order to hold the work in position while the projecting ends of the wire 11 are formed into the retaining coils, I provide in the present instance a clamp in the form of a shoe 13 which is supported at the bottom of a rod 14 55 guided vertically in a suitable guide 15 in the bracket 2 and normally held in a depressed work-engaging position by a spring 16 confined between the under side of the bracket arm 2 and a collar 17 at the upper 60 end of the shoe. Pivotally secured to the bracket at a point 18 adjacent the guide 15 is a bell crank lever, one arm 19 of which constitutes a handle, while the other arm 20 is in the form of a cam whose upper curved surface 65 engages a pin 21 on the stem 14 which projects through a slot 22 in the guide 15, as clearly illustrated. By manipulating the handle 19, the cam 20 may be oscillated upwardly, thereby elevating the stem 14 and the 70 shoe 13 from the table and the work which it normally engages.

The tool 5 forming the principal feature of the present invention consists of a cylindrical body portion having at its upper 75 end a cylindrical recess for reception of the lower end of the stem 4. In the present instance, a set screw 23 is provided by means of which the tool is rigidly secured to the shaft. Centrally of the lower end thereof and concentric with the axis of the shaft 4 is a projection 24 which as hereinafter set forth constitutes a mandrel around which the end of the wire 11 is coiled. The tool further comprises at a predetermined distance transversely from the mandrel 24 and also projecting below the lower end of the tool a cylindrical projection 25, this projection being of lesser length from the bottom surface of the tool body than the mandrel 24, as clearly shown 80 in Fig. 1. It will be noted that both the mandrel and the projection 25 are fixed with relation to the tool body.

In operation, the work is placed on the table 1, as illustrated in Fig. 1, with the wire 11 85 projecting through the sheets to be joined together. The work is so positioned on the table that the mandrel 24 when the tool 5 is lowered by pressing downwardly on the upper end of the shaft 4 engages the upper sheet imme- 100

dately alongside the upwardly projecting portion of the wire 11. The projecting end of the wire is turned down flat against the upper face of the sheet 9, as clearly illustrated. 5 The presser foot 13 having been permitted to engage the work, the operator first presses down on the shaft 4 until the mandrel engages the work, and in the working position as shown in Fig. 1, it will be noted that the projection 25 just clears the upper sheet 9. In order to bring the tool accurately into this position, I provide a shoulder 26 on the shaft 4 which in the present instance is adapted to engage the upper face of a sleeve 27 threaded 10 into a countersunk recess in the top of the guide portion 3 of the bracket 2. This sleeve 27 constitutes in effect an adjustable stop which limits the downward movement of the tool 5 and insures its being brought into 15 proper relation to the work by simple downward pressure on the upper end of the shaft or upon the arm 6. After the work has been engaged by the tool as set forth, the shaft 4 may be rotated through the handle 6 whereby 20 the projecting end of the wire 11 is engaged by the projection 25 and the wire carried in a series of convolutions around the mandrel 24 to form the coil 28, this coil lying flat against the upper face of the top sheet 9 and binding 25 this sheet and the sheet 10 securely together. Thereafter the sheets may be reversed to bring the opposite extremity of the wire 11 under the tool for formation of a similar retaining coil at the opposite end of 30 the wire, as illustrated in Fig. 3.

I have discovered that the form of tool described above constitutes a material improvement over the form shown in my aforesaid Patent No. 1,446,343. In that instance, the 40 mandrel was formed separately from the wire-engaging projections constituting the equivalent of the projection 25 of the present tool. Not only is that form of tool unnecessarily complicated and relatively expensive 45 to manufacture, but it actually is incapable of any more efficient operation than the tool forming the subject of the present invention.

It will be understood that the details of the tool as a whole may vary largely, as also may 50 the form of the finished fastener. In the present instance, a fastener is formed which constitutes in effect a staple whose ends are formed into flat coils, as clearly illustrated. In other types of fastener, the coils may be 55 formed at opposite ends of a straight wire which projects through the elements to be secured together.

I claim:

1. In a device for forming spiral wire fasteners, a rotatable body having at one end a projection concentric with the axis of rotation of said body and a second projection for winding the wire in spiral fashion around said first-mentioned projection, a work table 60 having a groove adapted to receive the said

wire and terminating at a point substantially in line with the axis of rotation of said body, means for axially shifting the body to bring the said projections into operative relation with work on said table, and means for rotating 70 the body.

2. In a device for forming spiral wire fasteners, a rotatable body having at one end a projection concentric with the axis of rotation of said body and a second projection for winding the wire in spiral fashion around said first-mentioned projection, a work table having a groove adapted to receive the said wire, means for shifting the said body so that the first-named projection lies immediately adjacent one end of said groove and said second projection is in position to engage a wire projecting from the groove, and means for rotating the body.

3. In a device for forming spiral wire fasteners, a rotatable tool comprising an axial mandrel element and a non-axial element adapted to engage the wire and to wind the latter in spiral fashion around said mandrel, a work table having a wire-receiving recess relatively positioned with respect to said tool to permit said tool to operate upon an end of wire projecting from said recess, and means for axially moving and for rotating said tool.

CHARLES P. GRAY.
